UNITED STATES PATENT OFFICE

HENRY KNUDSON, OF NEWMAN GROVE, NEBRASKA

SPINE CORRECTOR

Application filed January 11, 1930. Serial No. 420,171.

The present invention relates to devices adapted for massaging or correcting spinal defects.

An object of this invention is to provide a device for thoroughly massaging the vertebræ of the spinal column.

Another object of this invention is to provide a device which may be adjustably positioned on a wall or upright member and which may be used to massage the muscles of the back and the spinal column.

A further object of this invention is to provide a device which may be readily and cheaply manufactured and which is so constructed that it will not be easily injured during the massaging operation.

A still further object of this invention is to provide a device of this character which is so constructed as to have contact with all of the vertebræ in the spinal column so as to massage all of the members simultaneously.

The above and various objects and advantages of this invention will in part be described in and in part be understood from the following detailed description of the present preferred embodiment, the same being illustrated in the accompanying drawings wherein:

Figure 1 is a detail side elevation of a device constructed according to the preferred embodiment of this invention;

Figure 2 is a longitudinal section taken substantially through the center of the device; and

Figure 3 is a transverse section taken substantially on the line 3—3 of Figure 1.

Referring to the drawings wherein like numerals of reference designate corresponding parts throughout the several views, the numeral 10 designates generally an elongated base portion upon which are mounted a pair of parallel guide or supporting members 11 which are mounted upon the base in spaced relation to each other and are preferably adapted to have their opposite end portions protrude outwardly or beyond the opposite end portions of the base.

A spinal column corrector or massager generally designated as 12 is adjustably

mounted upon the parallel guide members 11. The massager 12 preferably comprises a pair of massaging members 13 which are mounted in spaced relation to each other and are provided with a depending or downwardly extending tenon 14 which is adapted to slidably engage between the parallel guide members 11. The massaging members 13 are preferably of a configuration to conform to the configuration of the spinal column and are provided with a plurality of upstanding rubbing or spinal column engaging members 15 which are spacedly positioned along the outer edge portion of the massaging members 13. The vertebræ engaging members 15 are preferably of substantially tapering configuration and are provided at the outer end portion thereof with rounded or blunt ends 16 so that the spine engaging members 15 may contact with the skin without injury or abrasion.

The base member 10 is preferably adapted to be mounted in substantially vertical position as on a wall or other vertical supporting member and the tenon member 14 is provided with a plurality of notches 17 in the inner edge portion thereof which are adapted to adjustably receive bolt members 18 which are positioned in the parallel guide members 11.

The bolt members 18 may be provided with a thumb nut 19 or the like so that the massaging member 12 may be positioned on the guide members 11 at the desired height. It is, of course, understood that the base member 10 may be also mounted in substantially horizontal position or, if desired, is provided with suitable handles or hand engaging members so that it may be manipulated by the hand.

The number of outwardly extending vertebræ engaging members 15 which are positioned on the massaging members 13 preferably conform to the number of vertebræ in the spinal column so that only a relatively slight movement of the massager is necessary in order to massage each vertebra.

In the preferred embodiment of this invention, the massaging member 13 is preferably constructed of wood or the like but it is, of course, understood that it may be

constructed of any other suitable material such as rubber, celluloid, metal or the like.

The vertebræ engaging members 23 are preferably spaced apart a sufficient distance 5 so as to massage the opposite sides of the vertebræ simultaneously.

In the use of this device, the base 10 is preferably mounted in substantially vertical position as on a wall or other vertical supporting member, and the massaging members 13 vertically adjusted so as to engage the spine of a person in substantially standing or upright position. The tenon 14 may be provided with a desired number of notches 10 17 so that the massager 13 may be moved upwardly or downwardly to the desired height. When the desired height has been determined, the thumb nut 19 may be tightened so as to firmly hold the massaging members 13 against movement whereupon the person desiring the treatment may stand in front of the device and place his spine against the massaging members 13.

The oscillating movement of the spine on 25 the engaging members 15 will thoroughly massage the vertebræ and thereby cure numerous ailments or the like resulting from dislocated or injured vertebræ.

It is of course understood that various 30 changes and modifications may be made in the details of construction and design of the above specifically described embodiment of the invention without departing from the spirit thereof, such changes and modifications 35 being restricted only by the scope of the following claim:

What is claimed is:—

A spine corrector of the character described comprising a base, a pair of longitudinally 40 disposed guide members mounted on the base, a spinal column massaging member adjustably mounted on the base, said massaging member comprising a pair of elongated massaging members having a plurality of outwardly converging vertebræ engaging means mounted thereon, and a longitudinally disposed tenon adapted to be positioned between said guide means, said tenon having a plurality of transversely disposed slots there- 45 through, and a pair of securing bolts carried by the guide means and engaging the tenon in selected slots thereof whereby to adjustably position the massaging means on the base.

50 In testimony whereof I hereunto affix my signature.

HENRY KNUDSON.
